TITLE AND TILE ASSEMBLY

Clements Batcheller, Glens Falls, N. Y., assignor
to Allegheny Ludlum Steel Corporation, a cor-
poration of Pennsylvania

Application October 1, 1937, Serial No. 166,829

6 Claims. (Cl. 189—85)

My invention generally relates to a novel composite tile, adapted for application to walls and the like, which comprises a facing element of lustrous metal of extremely light gauge and a backing element of flexible but substantially inelastic material, the metal facing element being characterized by its resistance to attack from all ordinary media while maintaining its lustrous surface under indefinite exposure to the atmosphere.

My invention more particularly relates to a tile comprising a thin, light gauge, corrosion resistant, alloy steel face having a highly reflective surface and one which does not become dull or tarnished as commonly results from oxidation in, for example, ordinary carbon steels. It is well known, too, that tarnishing or loss of lustre also occurs in common yellow metals.

The light gauge, metal sheets which I contemplate employing as the facing element of my tile are preferably of a thickness of the order of about .008" to .016". Obviously, such paper-thin metal sheets can not alone form tiles of commercial value due to their lack of adequate structural strength. Furthermore, since it is desirable to provide tiles with beveled edges, it would be extremely difficult to fabricate such structures from metals of a thickness above indicated. However, the desirability of using such thin, light gauge, metal sheets resides not only, for example, in their highly aesthetic and enduring properties but also in the low cost thereof per square foot and I have found that when such metal sheets are adequately reinforced by a suitable backing element, securely affixed thereto, a composite sheet product is produced having very suitable working qualities and of adequate structural strength.

For example, in my co-pending application, Ser. No. 101,924, filed September 22, 1936, I have disclosed a composite sheet product which I have found may advantageously be employed in the formation of my tile product and tiles of all practical sizes including conventional, 4" x 4", 6" x 6" and 3" x 6" tiles may readily be formed therefrom.

The facing element of such composite sheet or strip products may be formed from an alloy steel containing about 8% or more of chromium and, due to the cold rolling methods of production, such strips have a highly polished surface lustre and are highly resistant to corrosion. These strips, being of such thinness, say of the order of from .002" up to .016" are provided with a reinforcing, backing element having properties

adapted to overcome not only working difficulties inherent in the metal strip but also to furnish a satisfactory, bonding medium for the application thereof by means of a suitable adhesive to practically all types of wall surfaces including, by way of example, smooth board surfaces and the like. Cheap, flexible and substantially inelastic backing elements are found, for example, in a felted, cellulose-rag, fiber sheathing product, either impregnated with some substance such as asphalt, size or a resin compound, or dry. Another backing element may comprise a loosely felted bonded mineral fiber mat or even a flexible paper board product. The facing and backing elements are secured together preferably by means of a suitable cement or adhesive and subjected to relatively heavy external pressure.

I have found that a very satisfactory, flexible backing element for the composite strip which is employed in the formation of my tiles, comprises a smooth surfaced, asphalt impregnated, felt paper having a weight of about 28 pounds per 108 square feet. Incidentally, such paper may be provided with a painted or lacquered, exposed surface to enhance its surface smoothness and aid in the adhesion of the tile to a wall surface. A protective coating of this character also prevents bleeding of the impregnating compounds in the paper in those cases where the paper is subjected to high temperatures.

It is, therefore, an object of my invention to provide a tile formed from a composite strip of the foregoing described nature which tile, due to its novel construction, is adapted to be adhesively affixed to a wall surface or to be imbedded in and thereby secured to a wall while the wall is still in a somewhat plastic condition such as walls of wet plaster or concrete grout.

Further objects of my invention lie in a tile assembly wherein tiles, as a group, are applied to a wall, or, with like effect tiles are individually applied in predetermined relation and the spaces therebetween treated to simulate tile joints.

With these and other objects in view, my invention includes the novel constructions and the combinations and arrangements of elements described below and illustrated in the accompanying drawing in which—

Fig. 1 is a perspective view of a tile of my invention;

Fig. 2 is a sectional view illustrating one form of tile construction;

Fig. 3 is a sectional view illustrating a modified tile construction;

Fig. 4 is a fragmentary, sectional, perspective view of a tile similar to that of Fig. 3;

Fig. 5 illustrates a modified construction.

Fig. 6 illustrates, somewhat diagrammatically, 5 one method of forming my tiles;

Fig. 7 is a fragmentary illustration of a tile assembly;

Fig. 8 is a sectional view taken in about the plane 8-8 of Fig. 7;

Fig. 9 is a fragmentary plan view of a template or mounting element for the tile;

Fig. 10 illustrates a template, wall and tile assembly; and

Fig. 11 illustrates a fragmentary section of a 15 tile assembly wherein the tiles are mounted immediately adjacent each other.

Referring to the drawing, 1 indicates generally a tile provided with beveled edges 2 and formed from a composite strip having a facing and backing element of the nature herein referred to. The tiles are preferably blanked from a composite strip consisting of a thin metal facing 3 and a backing 4 adhesively secured thereto, and are beveled along the edges to afford an imbedded 20 simulation when affixed to a wall surface.

In Fig. 3, a modified formation of tile is illustrated wherein both the facing element 3 and the backing element 4 are beveled to form a tile having a slightly concave back adapted primarily 30 for application to plastic walls. In the preferred form of tile of this character, the backing element 4 is provided with a multiplicity of spaced indentations 5 which, when the tile is partially imbedded in a plastic wall, are adapted to be 35 filled with such plastic to form a strong bond between the tile and wall.

In view of the highly lustrous properties of the metallic sheet 3, I also contemplate providing a colored film of lacquer or other suitable product 40 to enhance the aesthetic appearance of the finished tile product. A protective coating of this character also serves to prevent disfigurement of the tile face from abrasion while permitting facile removal of adherent 45 films such as finger marks and the like. In Fig. 5, a protective film 6 is applied to the exposed surface of the metal element 3 and, it will be understood, I prefer to employ a translucent coating so that the highly reflective and 50 lustrous appearance of the metal facing sheet will not be lost.

For example, a suitable coating product is found in the proprietary product known as "Durtemp". This product, when applied to the 55 face of my tile and baked affords a coating which is resistant to practically all ordinary corrosive or solvent media, and being translucent, does not hide the lustrous appearance of the metal facing.

In Fig. 6, I have illustrated one method of forming the tiles of my invention. A blank 7 of the composite strip product is presented between the die 8 and die plate 9, the female die 8 being recessed with beveled edges 10 which are adapted, 60 when the die and die plate are forced together under pressure, to bevel the blank along the sides thereof to form the tile product illustrated in Fig. 2.

In forming a tile assembly by application of 70 the respective tiles in spaced relation upon a wall surface, as illustrated in Figs. 7 and 8, the appearance thereof may be greatly improved by applying colored strips to cover the visible portions of the wall surface intermediate the tiles. 75 For example, with the tile 1 arranged in the

manner illustrated and adhesively secured to the wall 11, areas 15 are apparent therebetween. In accordance with my invention, I contemplate adhesively securing strips 12, for example, of colored cellulose-acetate between the tiles to simulate tile joints, preferably of a contrasting color to the tiles. The strips 12 may be formed from any suitable, preferably translucent, material.

A modified tile assembly wherein the spaces 10 between the tiles may be provided of desired coloration comprises a sheet of suitable sheet material such as paper, preformed with colored zones intermediate those portions thereof designed to be covered by the tiles. As illustrated 15 in Figs. 9 and 10, a sheet 13 of paper or the like bears delineations 14 representing the areas 15 to be covered by tiles. The tiles may be first applied to the paper and thereafter a panel of tiles applied to the wall surface or, of course, the 20 paper may be applied to the wall, and the tiles adhesively secured thereto. Those portions 16 between the areas 15 of the sheet or template 13 are preferably colored to simulate joints of distinguishing appearance in the completed tile 25 assembly.

In view of the beveled construction of the tiles, they may be mounted in the manner illustrated in Fig. 11 wherein the tiles are shown mounted immediately adjacent each other. The beveled 30 sides of the tiles clearly present lines of demarcation whereby the appearance of tile joints is effected.

It is also desirable and my invention contemplates the provision of my tile products with a 35 light adhesive, preferably water soluble, protective coating on the face thereof. A coating of this character prevents impairment of the tile surface during transmission and installation and, of course, may be readily removed after the tiles 40 have been mounted. A coating of the foregoing character or one of suitable lacquer or paper may be used, and if desired, such coating may be applied to the composite strip product before the tiles are formed therefrom.

While I have described my invention in its preferred embodiments with considerable detail, it is to be understood that the words which I have used are words of description rather than of limitation and that changes within the purview of the appended claims may be made without departing from the true scope and spirit of my invention in its broader aspects.

What I claim is:

1. A composite tile unit for wall application 55 comprising a facing element of thin gauge, substantially stainless alloy metal, whereby the surface finish thereof is of a permanent character, and a backing element of flexible, non-metallic sheet material adhesively secured to and substantially coextensive with the back of said facing element; the marginal edges of said tile unit being beveled and said unit having a slightly concave back.

2. A composite tile unit for wall application 65 comprising a substantially flat facing element of thin gauge alloy steel containing at least 8% by weight of chromium, whereby the surface of said element is rendered substantially stainless, and a backing element of fibrous sheet material 70 adhesively secured to and substantially coextensive with the back of said facing element; the marginal edges of said tile being beveled and extending slightly beyond the major portion of the exposed face of the backing element whereby 75

to provide a tile unit having a slightly concave back.

3. A composite tile unit for wall application comprising a substantially flat facing element of thin gauge alloy steel containing at least 8% by weight of chromium, whereby the surface of said element is rendered substantially stainless, and a backing element of fibrous sheet material adhesively secured to and substantially coextensive with the back of said facing element; said facing and backing elements being beveled along the marginal edges thereof to form a tile unit having a slightly concave back.

4. The structure set forth in claim 1 in which the backing element is provided with spaced openings therein.

5. The structure set forth in claim 2 in which the backing element is provided with spaced 5 openings therein.

6. The structure set forth in claim 3 in which the backing element is provided with spaced openings therein.

CLEMENTS BATCHELLER.
